United States Patent Office

Des. 219,824
Patented Feb. 2, 1971

219,824

TRAMPOLINE FRAME

Richard W. Swanson, 6374 S. Lafayette Place,
Littleton, Colo. 80120

Filed Aug. 28, 1969, Ser. No. 18,887

Term of patent 14 years

Int. Cl. D21—03

U.S. Cl. D34—5

FIG. 1.

FIG. 2.

FIG. 3

FIG. 4

FIG. 5

FIG. 1 is a perspective view of the trampoline frame, showing my new design;

FIG. 2 is a top plan view thereof;

FIG. 3 is a side view thereof, the other side being a mirror image;

FIG. 4 is a bottom view thereof; and

FIG. 5 is an end view thereof, the other end being a mirror image.

I claim:

The ornamental design for a trampoline frame, as shown and described.
